BALL AND PIN CARRIER

Maurice O. Berg, Chicago, Ill.

Application April 12, 1941, Serial No. 388,232

9 Claims. (CL. 273—43)

This invention relates in general to bowling alleys and is more particularly described as a bowling ball and bowling pin carrier used in connection with standard bowling alley equipment which is operated from the pit at the rear of a bowling alley.

As now operated, the balls and pins are lifted manually from the pit at the rear of a bowling alley to deposit the ball upon the ball return rack and the pins upon the carrier of the pin setting equipment.

The present invention provides a carrier for receiving a bowling ball and from 1 to 10 bowling pins in the pit at the rear end of a bowling alley, and by counter-weighting the carrier, provides means for manually raising the ball and pins to the approximate level of the ball return track and closely adjacent the mechanical pin setter with a minimum manual effort.

By use of this equipment, one pin setter is able to take care of two adjacent alleys in less time and with less manual labor than is now required to set pins on one alley.

This invention consists in the provision of a ball and pin carrier as an addition to or an attachment for bowling alley equipment, using the automatic pin setting device having a raised holder in which the pins knocked down are deposited after each ball is thrown, although the attachment may also be applied to a new equipment of this type.

Other objects of the invention will be described in the specification and will be apparent from the accompanying drawings in which

Fig. 1 is a plan view of the pit ends of a pair of adjacent bowling alleys illustrating this invention as applied thereto;

Fig. 2 is a perspective of the under side of a ball and pin carrier as shown in Fig. 1;

Fig. 3 is a sectional view as taken on the line 3—3 of Fig. 1, showing the ball and pin carrier in receiving or lowered position; and

Fig. 4 is a view showing the movable parts of Fig. 3 in a raised or discharging position.

A bowling alley pin setter is required to lift a bowling ball weighing approximately 16 pounds to a height of about 3 feet to the ball return rack each time the ball is played and to collect and deposit the ten bowling pins each weighing approximately 3 pounds to the level of the pin setting equipment. This requires from three to six manual operations for each time the pins are knocked down and reset. By providing a counter-weighted carrier, these numerous and laborious manual operations are reduced and a semi-

automatic operation is substituted so that one attendant can easily set pins on two alleys. This will tend to speed up the game, reducing the time and labor, making possible a saving in the labor costs and increased revenue for the bowling alleys.

Referring now more particularly to the drawings, the pit end of a regulation bowling alley 10 is shown having gutters 11, side walls 12, a rear wall 13 protected by a bumper pad 14, a ball return track 15 and providing a pit 16 above a floor 17 at the rear end of the alley for receiving the pins or deadwood knocked down by the ball and the ball after it has been thrown.

A number of bowling pins 20 are set upon the alley in regular formation to be knocked down by a ball 21 and above the setting position is an automatic pin setting device comprising a movable holder 22 which is raised above the alley, the pins are deposited therein and the setting device is lowered, automatically positioning the pins on the surface of the alley in a well known manner.

The ball and pin carrier of this invention is adapted to fit into the pit at the rear of each bowling alley and comprises a bottom 24 formed of fiber, wood, or light sheet metal and having opposite upright ends 25 with front and rear sides 26 and 27 secured to the bottom by spring hinges 28. In its pit position, the sides are supported in partially inclined position by blocks 29. One side 26 is supported with its upper edge just below the edges of the gutter 11 so that the ball or pins may be swept freely therefrom into the carrier.

At each end of the carrier is a lever 30 mounted to swing on a pivot 31 at the inner side of the adjacent wall 12 and at a height to offer no obstruction to the ball or to the pins from the alley. At the free end of each lever which extends to the rear of the pit is a hand grip 32, and adjacent the end is a pivotal connection 33 with the adjacent end 25 of the carrier.

Connected to the lever and projecting oppositely from the pivoted end is an arm 34 upon which a counter-weight 35 is slidable and adjustable. Adjustment is provided so that the counter balance may be varied easily to equalize, over-balance or under-balance the weight of the carrier and contents and thus to accommodate balls and pins of different weight.

The rear side 27 of the carrier may be connected to the lever 30 adjacent the handle by a link 31 pivoted at the ends thereto so that when the carrier is raised by the handle, the side 27

will also be raised. At this time, the front side 26 will extend under the holder 22 of the pin setting device. When the carrier is raised, the rear side 27 is raised, thus tending to prevent accidental dislodgment of the pins or balls therefrom, and the close engagement with the movable holder 22 facilitates the transfer of the pins to the holder 22 and the balls from the carrier to the track 15.

To adjust the position of the counter-weight 35 on the arm 34, a rod 42 is pivoted at one end to the weight and at the other end to a hand lever 43 which is pivoted at its lower end to the carrier mounting lever 30. A toothed segment 44 is secured to the lever 30 at the base of the hand lever, and a spring pressed latch 45 has a grip near that of the hand lever 43, so that the lever and latch may be manually engaged and the counter-weight easily and quickly adjusted and set in position to balance one or more of the balls or pins in the carrier.

One weight 35 may have a more or less fixed position along its arm 34 but may be adjustably set in any desired location along the arm by a bolt or set screw 36. By having the weights thus adjustable, the carrier and its contents may be most easily counter-balanced, and the counter-balance varied for different loads.

Instead of the counter-weight projecting forwardly from the pivoted end of the lever 30, any other suitable counter-weight may be employed such, for example, as a spring at the pivot 31 engaging the lever, or a cable supported weight attached at or near the free end of the lever and extending upwardly therefrom in any well known manner.

When this construction is applied to a pair of adjacent bowling alleys, an attendant usually sits upon a rail 40 at the top of the wall 20 between the alleys, lifting or throwing his feet from one side to the other to avoid the balls and the flying pins as they are struck by the balls, and so that he may step into the carriers for gathering the pins and balls therein. At the bottom of the carrier is a pad 41 of fabric of sound deadening material. This attendant may reach down from either side of the wall, adjust the position of the weight, if desired, grasp the handle end of the lever on the other side thereof and thus raise the entire carrier and its contents to the approximate level of the pin holder and ball track.

It is apparent that various other changes in the construction, combination, and arrangement of the parts may be made for carrying out the purpose and object of this invention without departing from the spirit and scope thereof.

I claim:

1. The combination with a bowling alley having a ball and pin receiving pit, a movable normally raised pin setting holder, and a raised ball return track, of a ball and pin carrier to fit in the pit, and means comprising levers pivoted at the inner sides of the alley and pivotally mounting the carrier thereon for movement from the pit approximately to the height of the holder and track.

2. A bowling alley attachment comprising a ball and pin carrier to fit loosely in the pit at the end of the alley, and comprising levers each pivoted at one end at each side of an alley and pivoted intermediate its ends to the carrier for

mounting the carrier to move upwardly from the pit to raise balls and pins therein to a height for manual horizontal transfer to the ball track and pin setter of the alley.

3. A bowling alley attachment comprising a ball and pin carrier to rest in the pit at the end of the alley, and means manually movable by an operator in the pit comprising levers mounted at the sides of the alley and pivoted to the carrier for raising the carrier to a predetermined height approximately that of the ball return track and raised pin setter of the alley.

4. In a bowling alley attachment, a ball and pin carrier positioned in the end pit, means comprising a lever at each side pivoted at one end to the side of an alley and pivotally connected to the carrier for raising and lowering it from and to the pit to the approximate level of the ball track and raised pin holder of the alley, and a counter-weight connected to each lever for counter-balancing the carrier and its contents.

5. A bowling alley accessory comprising a ball and pin carrier for the end pit, mounting means comprising levers manually operable from the inside of the pit pivoted at one end to the side wall of the alley and near the other end to the carrier and adapted to raise the carrier approximately to the level of the ball track and raised pin holder of the alley, and adjustable counter-weight means connected to the levers for variably counter-balancing the carrier.

6. In a bowling alley attachment, a ball and pin carrier for the end pit, hinged front and rear sides for the carrier, manually movable means actuated from the inside of the pit for moving the carrier from and to the pit, and supporting blocks at the front and rear of the pit for holding the said sides of the carrier inclined when it is seated therein.

7. In a bowling alley accessory, a ball and pin carrier for the end pit, means manually operable from the inside of the pit for moving the carrier from the pit, the front side of the carrier being hinged thereto, and a block in the front of the pit to support the side in raised position with its top above the bottom of the gutters along the sides of the alley.

8. In a bowling alley attachment, a ball and pin carrier for the end pit, means manually operable from the inside of the pit and comprising a lever for moving the carrier from and to the pit, the rear side of the carrier being hinged thereto, and a hinged link connecting the rear side and the lever and operative to incline the side partially in the pit position and to raise it more nearly to an erecting position when the carrier is raised.

9. In bowling alley equipment, the combination with an alley having side gutters, an end pit, and a raisable pin setting holder, of a ball and pin pit carrier, means manually operable from within the pit for raising the carrier from and returning it to the pit, the carrier comprising hinged front and rear sides, the front side swinging downwardly and engaging below the rear end of pin holder in its raised position and disposed in the pit in lowered position, and the rear side being connected to and inclined upwardly by the said carrier raising means in the raised position of the carrier.

MAURICE O. BERG.
